UNITED STATES PATENT OFFICE

WILLIAM A. SCHATZ, OF ASTORIA, NEW YORK

DISPENSER

Application filed November 7, 1927. Serial No. 231,423.

This invention relates to dispensing devices, and more particularly, to dispensers for beverages in which the beverage is both displayed and either refrigerated or heated.

A general object of the invention is to provide a device of the type described which may be easily and economically manufactured, shipped and assembled, which efficiently displays and dispenses the beverage, which lends itself to long-continued operation in that it may be quickly and easily refilled and re-iced when used for cooling, and may be readily cleaned.

A more specific object is to provide a device which is portable, light and compact, and in which the beverage may be completely surrounded by cold or hot treating liquid while being displayed to advantage therethrough.

Other objects of the invention will in part be obvious and in part will appear hereinafter.

The invention accordingly comprises the features of construction, combination of elements and arrangement of parts which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Figure 1 is a quartered rear elevational view of one embodiment of the present invention;

Fig. 2 is a front elevational view;

Fig. 3 is a vertical sectional view taken on the broken line 3-3 of Fig. 2 looking in the direction of the arrows;

Fig. 4 is a horizontal sectional view taken on the line 4-4 of Fig. 3 looking in the direction of the arrows;

Fig. 5 is a horizontal sectional view taken on the line 5-5 of Fig. 4 looking in the direction of the arrows;

Fig. 6 is a view similar to Fig. 4, showing a slightly modified form of the device;

Fig. 7 is a view similar to Fig. 5, showing another modification; and

Fig. 8 is a fragmental vertical sectional view of a further modification taken along a plane corresponding to the sectional plan of Fig. 3.

In the drawings, the numeral 10 designates generally the outer casing of the device which is provided with a top 11 and may be mounted upon a base 12. The casing 10 is composed of upper and lower sections 13 and 14 which have heat-insulating properties, and, in a preferred form, are composed of two sheet metal walls, between which is interposed an insulating material 15. In the bottom section 14, the insulating material is also carried across the bottom of the device, as at 15'. 55

Disposed between the sections 13 and 14, and comprising a third section of the external casing 10, is a circumferential transparent portion 16, which is made of glass or the like. The edges of the member 16 are disposed snugly within the adjacent ends of the members 13 and 14, which, in turn, are clamped onto the member 16 by suitable clamps or members 17. The casing 10 is liquid-tight and is adapted to hold a treating liquid, i. e., either a refrigerant or a heated liquid, around a beverage-containing compartment, as will be hereinafter described. 60 In order to prevent leakage of said treating liquid, suitable gaskets 18 preferably are disposed between the member 16 and the members 13 and 14. Also, if desired, the section 16 may be double-walled, as shown at 16' in Fig. 8. With this construction, accumulation of moisture on, and clouding of, the outside surface is prevented, and improved insulation is attained, due to the dead air space between the walls. 70

Disposed within the external casing 10 is a transparent beverage container 19, which 75 preferably has a relatively slender neck-portion 20 and is tightly closed by a gasket 21 and top 22.

Preferably just above the upper edge of the transparent member 16 the wall of the member 19 is extended outwardly and downwardly throughout a considerable portion of the periphery thereof so that the portion 23 is disposed concentrically to the member 16. 85 It will thus be seen that the space between the 90

neck 20 and the section 13, may, when the device is used for dispensing beverages cold, be filled with ice and that ice water will soon fill the annular space between the member 16 and the member 23.

5 The portion of the member 19 which is not widened is deformed so as to form an ice pocket 24 and a relatively flat portion 25 through which the faucet connection 26 may be passed. 10 As is obvious, when ice is placed around the neck 20 of the member 19 a portion thereof will slide downwardly into the ice pocket 24 and will efficiently cool the beverage in the bottom part of the container 19 and in the 15 faucet connection 26.

A faucet 27 is disposed externally of the member 14 and passes therethrough to connect with the member 26. Although this faucet may be of any suitable construction, 20 it is preferred that it should be constructed substantially in accordance with the device shown in my copending application Serial No. 64,681, filed October 24, 1925.

With this construction there is provided an 25 agitating member 28 supported upon a shaft 29 which is connected to the faucet handle 30, whereby when the faucet is opened by turning the handle the member 28 agitates the beverage. Such construction is particularly 30 desirable in the case of beverages which contain suspended matter which tends to settle out, whereby a liquid of uniform consistency may be drawn and also aids in maintaining a uniformity of temperature in the beverage.

35 As is usual in beverage dispensers, the device is provided with a water drain 31. Also, as is shown in Figs. 6 and 7, the beverage container 19 may be provided with a plurality of icing pockets 24', or it may be replaced by a 40 plurality of nested individual containers 19', whereby a plurality of beverages may be dispensed from the same cooler.

Finally, as will be seen by further reference to Fig. 8, the container 10 may be provided, if desired, with a heating element 32, to maintain an elevated temperature in the treating liquid when dispensing hot beverages. This element may be of any type, as, 45 for example, an insulated resistance element, through which electric current may be passed.

Also, although it may be positioned as desired, it is particularly effective when positioned within the insulated section 15 and around the neck of the beverage container 19, 50 since in this position it not only effectively heats the beverage, but, if by chance the treating liquid should boil, this action will not obscure the display of the beverage. Furthermore, when positioned adjacent the neck 60 of the beverage container or the inside wall of the section 15 of the casing 10, this element may be allowed to remain in the device even when dispensing cold beverages, and will not appreciably interfere with the icing 65 of the device.

Although reference has been made above to an electrical heating coil and to ice as a refrigerating agent, it will be readily understood to one skilled in the art that, if desired, other heating or refrigerating means can be utilized without departing from the spirit of this invention; for example, the coil 32 may comprise a coil pipe, which, when dispensing hot beverages, may carry steam or other heating fluid, and when dispensing cold beverages may carry a cooling medium, such as brine or the like. In either case, as will be understood, the coil must be surrounded by a liquid which comes within the generic term "treating liquid" above referred to.

70 It will thus be seen that particularly efficient type of cooler is provided which is so constructed that it may be placed on counter with the faucet and ice water drain extending inwardly, whereby an unobstructed view of the contents of the main portion of the beverage container can be viewed by the customer at the front side of the counter.

75 It might also here be pointed out that, owing to the concentric construction of the transparent member 16 with the wall 23 of the beverage container, the ice water forms a uniform film of liquid which is interposed between the beverage and the customer whereby the appetitive appeal is enhanced. Although the external casing 10 has been shown as having an annular cross section, it is to be understood that any equivalent configuration may be employed without departing from the 80 spirit of the invention.

85 Since certain changes may be made in the above construction, and different embodiments of the invention could be made without departing from the scope thereof, it is intended that all matter contained in the above description or shown in the accompanying drawings shall be interpreted as illustrative and not in a limiting sense.

90 It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A device of the class described, including, in combination, a beverage container composed of transparent material and an externally-disposed liquid-tight container having a circumferential transparent portion in registry with a portion of said beverage container and disposed substantially parallel to the walls thereof; said beverage container being relatively free from light-impeding elements whereby light may pass freely and diametrically through the device in the area of the circumferential transparent portion. 100

2. A device of the class described, comprising in combination a liquid-tight container having upper and lower insulated sections, a transparent section intermediate said insulated sections, a beverage container disposed in said first-mentioned container and having a transparent wall adjacent said transparent section of said first-mentioned container. 5
3. A device of the class described, comprising a liquid-tight container having an insulated and a transparent section, a beverage container disposed in said first-mentioned container and having a transparent wall adjacent said transparent section of said first-mentioned container, said transparent portion of said beverage container being disposed substantially parallel to said transparent portion of said first-mentioned container for a considerable portion of its area, the remainder of its area being deformed to provide a pocket. 10
4. A device of the class described, comprising an annular liquid-tight container having upper and lower heat-insulated sections and an intermediate transparent section, each of said sections forming an annular band, a beverage container disposed within said first-mentioned container, said beverage container having a transparent portion disposed adjacent to and substantially concentrically with said transparent portion of said first-mentioned container for a considerable portion of its periphery, and being deformed for the remainder of its periphery to provide a pocket. 15
5. A device of the class described, comprising an annular liquid-tight container having upper and lower heat-insulated sections and an intermediate transparent section, each of said sections forming an annular band, a beverage container disposed within said first-mentioned container, said beverage container having a transparent portion disposed adjacent to and substantially concentrically with said transparent portion of said first-mentioned container for a considerable portion of its periphery, and being deformed for the remainder of its periphery to provide a pocket. 20
6. A device of the class described, comprising an annular liquid-tight container having upper and lower heat-insulated sections and an intermediate transparent section, each of said sections forming an annular band, a beverage container disposed within said first-mentioned container, said beverage container having a transparent portion disposed adjacent to and substantially concentrically with said transparent portion of said first-mentioned container for a considerable portion of its periphery, and being deformed for the remainder of its periphery to provide a pocket, the upper part of said beverage container having a relatively small neck-portion whereby a considerable space is provided between this portion and the first-mentioned container. 25
7. A device of the class described, comprising an annular liquid-tight container having upper and lower heat-insulated sections and an intermediate transparent section, each of said sections forming an annular band, a beverage container disposed within said first-mentioned container, said beverage container having a transparent portion disposed adjacent to and substantially concentrically with said transparent portion of said first-mentioned container for a considerable portion of its periphery, and comprising a plurality of deformed portions forming pockets. 30
8. A device of the class described, comprising an annular liquid-tight container having upper and lower heat-insulated sections and an intermediate transparent section, each of said sections forming an annular band, a plurality of beverage containers, each of said beverage containers having a transparent portion disposed adjacent to and substantially concentrically for a considerable portion of its periphery with a portion of said transparent portion of said first-mentioned container, and each having a deformed portion forming a plurality of pockets. 35
9. A device of the class described, comprising an annular liquid-tight container having upper and lower heat-insulated sections and an intermediate transparent section, each of said sections forming an annular band, means for releasably retaining said sections of said first-mentioned container in assembled position, a plurality of beverage containers, each of said beverage containers having a transparent portion disposed adjacent to and substantially concentrically for a considerable portion of its periphery with a portion of said transparent portion of said first-mentioned container, and each having a deformed portion forming a plurality of pockets. 40
10. A device of the class described, comprising, in combination, a beverage container having a curved transparent portion and an externally-disposed curved liquid-tight container having a portion in registry with said first-mentioned transparent portion and disposed substantially concentrically therewith, said second-mentioned portion being transparent and composed of spaced walls. 45
11. A device of the class described, comprising, in combination, a beverage container having a curved transparent portion and an 50

externally-disposed curved liquid-tight container having a portion in registry with said first-mentioned transparent portion and disposed substantially concentrically therewith, said second-mentioned portion comprising spaced transparent wall-members having an air space therebetween.

12. A device of the class described, including, in combination, a beverage container having a curved transparent portion, an externally-disposed curved liquid-tight container having a transparent portion in registry with said first-mentioned transparent portion and disposed substantially parallel thereto, and a temperature-controlling coil disposed between said containers.

13. A device of the class described, comprising an annular liquid-tight container having an upper heat-insulated section and 20 a transparent section positioned below the same, each of said sections forming an annular band, a beverage container disposed within said first mentioned container, said beverage container having a transparent portion 25 disposed adjacent to and substantially concentrically with said transparent portion of said first mentioned container for a considerable portion of its periphery, and being deformed for the remainder of its periphery 30 to provide a pocket.

In testimony whereof I affix my signature.
WILLIAM A. SCHATZ.
